UNITED STATES PATENT OFFICE

FRANK B. LUTMAN, OF COLUMBUS, INDIANA, ASSIGNOR TO COLUMBUS HANDLE & TOOL CORPORATION, OF COLUMBUS, INDIANA, A CORPORATION OF INDIANA

TOOL HANDLE

Application filed September 22, 1930. Serial No. 483,539.

My invention relates to handles of the class used upon spades, shovels and some other tools which consist of a bifurcated element having its branches connected at their ends by a transverse holding or hand-gripping member, and of the type of such handles in which the forked member is formed of sheet metal stamped into suitable form to form at its base a stale socket engaging a wooden stale member and having the two branches formed with a pair of terminal grip sockets arranged to be connected to a wooden cross-grip which extends between them. The object of my invention is to provide improved means for locking the wooden grip member in the sockets in a simple, sightly and secure manner, so that the appearance of the handle will not be marred, yet the grip member will be so effectively held that it cannot get loose and chatter, even after considerable usage. It has been found that the various forms of locking lugs, fins, or other protuberant members heretofore employed in the prior art, so far as known to me, are all subject to becoming loose and chattering under any usage which produces frequent or constant jarring of the handle, and the object of my invention is to obviate this defect in a desirable and effective manner. To this end I have devised the tool handle hereinafter described in detail, the essential elements of my invention being more particularly pointed out in the appended claims.

Figure 1 of the drawings illustrates a tool handle having a bifurcated sheet metal member engaging a wooden grip and provided with locking means embodying my invention;

Fig. 2 is an end or face view of the outside of one of the grip sockets, showing the shape of the cut which is made in forming the locking spurs;

Fig. 3 is a fragmentary vertical diametrical section of the same portion of the handle as that illustrated in Fig. 2, showing the locking spurs bent inwardly and imbedded in the grip, the plane of the section being indicated by the dotted line 3-3 of Fig. 1; and

Fig. 4 is a view of a suitable tool for forming the locking spurs.

Like reference characters indicate like parts in all the figures of the drawing.

The exact pattern of the sheet metal member of a tool handle to which my invention is applicable may vary in several respects, so long as it is formed to provide at the ends of the two branches 1-1 of the handle inwardly-facing cup-shaped grip sockets 2-2. The ends of the wooden grip 3 of the handle are seated snugly within these sockets, and the whole secured firmly and rigidly together by a bolt 4 extending longitudinally through the grip and riveted at its ends as securely as possible to said sockets. Preferably, and according to common practice, the bolt extends through the grip eccentrically of the sockets, as illustrated, so that it is incapable of rotating in the sockets.

The handle having been constructed and the parts assembled and secured together as thus far described, the grip sockets and grip are afterwards locked together in a novel manner now to be described, to form the completed handle. By means of a suitable punching tool *a*, see Fig. 4, the metal of each grip socket is cut upon two parallel lines and a transverse central line, approximately in the shape of the letter H, as illustrated in Fig. 2, so as to provide two rectangular spurs 5-5 lying between the parallel cuts and having their free edge directed towards each other from opposite bases connected to the uncut metal, and as these spurs are cut and formed they are forced or driven down into the wood by continued application of the tool until they are imbedded in the wood as a pronounced angle to the original position of the metal. Both grip locks may conveniently be made at the same time by means of a suitable press.

It has been found that the locked engagement of the grip sockets to the wooden grip thus provided forms a much more secure and permanent connection in respect to maintaining tightness and prevention of the chattering arising from jarring and severe usage than any of the more or less rounded or con-

vex forms of projections heretofore employed. The square-cut side edges and ends of the two spurs tend rather to become imbedded the more firmly in the wood of the grip by any expansion of the wood which may occur along their side edges and between their ends subsequent to application of the pressure by which the spurs are forced into place, than to become loose.

10 I claim:

1. In a handle of the type described including a bifurcated sheet metal member formed with terminal opposed grip-sockets, a transverse wooden grip and a bolt extending longitudinally through said grip arranged to secure said grip between said sockets, means for locking said grip in said grip-sockets comprising a pair of rectangular spurs struck inwardly from said sockets and imbedded in the adjacent end of the wooden grip, said spurs being cut upon parallel side lines and a transverse intermediate line defining the ends of the spurs.

2. In a handle of the type described including arms provided with terminal sheet metal grip-sockets opposed to each other, a transverse grip formed of wood and having its ends positioned in said sockets, means for securing the sockets to the grip to prevent separation of the same, and locking means comprising adjacent converging spurs struck inwardly from each sheet metal socket and compressing the wood under them.

3. A handle of the type described including arms provided with terminal sheet metal grip-sockets opposed to each other, a transverse wooden grip, a securing bolt extending through the sockets and the grip, and a pair of spurs struck inwardly from one of the sheet metal sockets, the spurs being cut so that they are opposed to each other, their lines of bending are parallel, and their edges are substantially radial with respect to the grips.

45 In testimony whereof, I have subscribed my name.

FRANK B. LUTMAN.
